UNITED STATES PATENT OFFICE.

EUGENE FONTAINE, OF TOLEDO, ASSIGNOR OF ONE-HALF TO WILLIAM A. KETTENRING, OF DEFIANCE, OHIO.

RAILROAD-CROSSING.

SPECIFICATION forming part of Letters Patent No. 327,670, dated October 6, 1885.

Application filed June 25, 1885. Serial No. 169,711. (No model.)

To all whom it may concern:

Be it known that I, EUGENE FONTAINE, of Toledo, in the county of Lucas and State of Ohio, have invented new and useful Improvements in Railroad-Crossings; and I do hereby declare that the following is a full, clear, and exact description thereof, reference being had to the accompanying drawings, which form a part of this specification.

10 This invention relates to certain new and useful improvements in the construction of railway-crossings of that class where one railway crosses another on a grade common to both and at any necessary angle.

15 As such crossings are usually made there is a great noise and much jarring, causing annoyance to the passengers, danger of derailing, and frequent breaking of wheels, and many other accidents are the consequent results of the 20 faulty construction now in ordinary use.

The object of this invention is to so construct such a crossing that all these difficulties are avoided, and in effect a continuous rail is presented to the passing train.

25 The invention consists in the peculiar construction of the various parts, and their combination and operation, whereby the desired result is obtained, all as more fully hereinafter described.

30 Figure 1 is a plan view of my improved crossing, the two railways running at right angles to each other. It will be obvious, however, to the experienced observer that the angle of crossing is immaterial. Fig. 2 is a plan view 35 of one of the corners of the crossing, all the other three corners being of a similar construction. Fig. 3 is a central vertical longitudinal section of one of the corners. Fig. 4 is a lateral section, showing the manner of securing the 40 ends of the rails to the plate. Fig. 5 is an elevation of the center post detached. Fig. 6 is a plan view of the spring detached.

In the accompanying drawings, which form a part of this specification, A represents the 45 track-rails of the roads, which cross each other at the point shown in Fig. 1.

H and P represent the top and bottom plates of the rail-supports, which rest upon the ties L, and are connected together by the web O, which 50 forms a rib or brace between the top and bot-

tom plates, and this web is cut away at the center to furnish room between such plates for the operating parts.

N is a part of a clip, preferably cast integral with and upon the upper face of the rail-supporting plate, and M forms the other part of the clip, and between these parts of the clip the ends of the rails A are slipped and secured by means of bolts a. Thus the ends of the four sections of rail necessary to form one section 60 or arm of the crossing are presented toward each other, as shown in Fig. 2, and their adjacent ends are cut out to form, as nearly as possible, the round hole b, which is coincident with a correspondingly shaped and sized hole 65 through the center of the top plate in the rail-support.

E is a step secured to the inner face, and at the center thereof, of the bottom plate of such rail-support, and in vertical axial line with the 70 center hole in the top plate, and between the adjacent ends of the rails, and above described as b.

B is a round post stepped in the step E, and is of sufficient length to project upward through 75 the top plate, so that its upper end is presented through the opening b and upon the same plane with the top surface of the rails A. To this post there is secured a toothed segment, D, which engages with the worm I upon the 80 shaft G, which is journaled at each end in the bearings F, which are cast upon or otherwise secured to the under face of the top plate of the rail-support. This shaft G extends from one corner of the crossing to the opposite corner, as shown in Fig. 1, and near each end is secured a worm, I, to engage with the segment at its respective corner, and as the post B at each of their corners must rotate in opposite directions the worm at one end of the shaft is 85 a right, and at the other end a left hand one. The top of the post B is cut out, as at Q, to allow the passage of the flange of the wheel of the car in passing, while the head of the post fills the space between the adjacent ends of the 90 rails, and in effect forms a continuation of such rails and allows the train to pass without jar or noise more than is created upon any continuous rail. As there are four corners at each crossing the above construction must be du 95

licated in order to insure success, and it is necessary that each corner should move simultaneously with the other. I connect each one of the worm-shafts, by means of suitable gears, 5 K, with a shaft, S, the free end of which may terminate at any desired position, and provided with any necessary mechanism by which it can be rotated.

In Fig. 1 the continuous track is shown as 10 running north and south. Now, if a train is approaching on the east and west track, the operator, by a partial rotation of the shaft S, gives a quarter-turn to the rotating posts B and puts that track into continuous connection.

15 If desired, the necessary signals may be so arranged and interlocked that the movement of the shaft S, as described, may at the same time operate the signals as well as the posts.

As the center of the rail supports is cut out, 20 as shown and described, the upper plate may spring downward at the center, where it is unsupported by the web O, in which case there would be a jar by reason of any such downward spring, as the head of the posts B would 25 project above the plane of the top of rails. To avoid this I interpose between the bottom of the top plate of the rail-support and the top of the segment the spring C, the effect of which is to hold the unstiffened parts from such 30 depressions.

Of course if there is a sufficient stiffness of 35 metal in this upper plate to withstand the tendency to spring at this point under the weight of the passing train the spring will not be necessary.

Of course there are four rail-supports, stelli-

form in shape, as shown in Fig. 2, one for each corner of the crossing, and these are bolted together, as shown in Fig. 1, so that the entire crossing is made very rigid.

I am aware that rack-and-pinion gearing has 40 been used in devices of this class for operating the movable portion at the intersection of the rails, and disclaim their use.

I attach importance to the worm-gearing 45 shown and described, for by its use I am enabled to provide against accidental displacement of the said section—a result which often accrues from the use of rack and pinion.

What I claim as my invention is— 50

1. In a railway-crossing having a rotating post at each intersection thereof, a rail-support consisting of an upper and under plate and supporting-web between the two, in combination with clips for securing the rails to the 55 upper plate, substantially as set forth.

2. In a railway-crossing constructed substantially as described, and in combination with the rail-support, a spring which will counteract any tendency of such support to deflect 60 under the weight of passing trains, substantially as specified.

3. In a railway-crossing, a rail-support consisting of an upper and a lower plate and supporting-web between the two, said web being 65 cut away at the center, and the rotating post carrying a segment operating in the cut-away portion of said web, substantially as described.

EUGENE FONTAINE.
